UNITED STATES PATENT OFFICE.

JOSEPH RENÉ AYOTTE, OF CHICAGO, ILLINOIS.

WRENCH OR OTHER TOOL.

1,424,794.

Specification of Letters Patent. Patented Aug. 8, 1922.

Application filed January 29, 1920. Serial No. 354,545.

To all whom it may concern:

Be it known that I, JOSEPH RENÉ AYOTTE, a citizen of the Dominion of Canada, and a resident of Chicago, Illinois, have invented 5 a certain new and useful Improvement in Wrenches or Other Tools, of which the following is a specification.

This invention relates to wrenches of that particular kind in which the socket end 10 which is formed to engage the nut or head of the bolt is turned and deflected laterally, so that the handle or shank portion of the wrench or tool may extend at an angle to the axis of the bolt, to suit the convenience 15 of the user, when the tool is used in situations where an ordinary wrench would not be suitable, and in which a rotatable handle is provided at the other end of the tool for the purpose of rotating the socket piece 20 which engages the nut or head of the bolt, whereby the shank or body of the tool may be held by one hand while the rotatable handle is operated by the other hand, thereby to turn the nut or head of the bolt in 25 the usual or ordinary manner.

Generally stated, the object of the invention is to provide a novel and improved construction involving certain details and features of construction and combinations tending 30 to increase the general efficiency and the desirability of a wrench or tool of the foregoing general character.

Some special objects of the invention are to provide an improved construction and arrangement whereby the extension tube is 35 readily detachable from the shank or body of the tool, when such is necessary or desirable; to provide an improved construction and arrangement whereby a key groove 40 is formed in the slidable or extension tube, which affords or insures certain advantages over previous constructions in which the groove was formed in the rotatable tube which is inside of the shank or body of the 45 tool; to provide an improved construction and arrangement whereby the transverse rod which forms a part of the rotatable handle is held in place by a spring-pressed friction button, in a better and more satisfactory 50 way than heretofore; to provide an improved construction and arrangement whereby the socket piece which engages the nut or head of the bolt may be easily rotated by the thumb or finger, in starting 55 the rotation of a nut or bolt, in situations where the initial rotation is more satisfac-

tory when produced this way than when it is attempted to accomplish this by rotation of the handle at the other end of the tool; and to provide the shank or body of the tool with a pair of knurled portions which are spaced apart to indicate the proper position of the hand when the wrench is used under different circumstances, or when the tool is lengthened or shortened by a sliding movement of the extension tube, as will herein-after more fully appear.

To these and other useful ends the invention consists in matters hereinafter set forth and claimed, and shown in the accompanying drawings, in which—

Fig. 1 is a side elevation of a wrench or tool embodying the principles of the invention.

Fig. 2 is a side elevation of the handle and ratchet portion of the said wrench or tool, showing the ratchet adjusted for operation in the opposite direction.

Fig. 3 is a longitudinal section of the said wrench or tool.

Fig. 4 is a perspective of the lower key employed in the construction of the tool.

Fig. 5 is a perspective of a screw threaded cap which, when removed, permits the slidable or extension tube which contains the groove for said key to be drawn out and separated from the other tubes.

Fig. 6 is an enlarged sectional view of the lower or socket end of the wrench, showing a supplemental socket piece inserted therein, thereby to engage a nut or bolt head of smaller size.

Fig. 7 is an enlarged cross section on line 7—7 in Fig. 3.

Fig. 8 is an enlarged cross section on line 8—8 in Fig. 3.

Fig. 9 is a perspective of the slidable ring which constitutes the means for reversing the operation of the ratchet.

Fig. 10 is an enlarged side elevation of a portion of the slidable or extension tube, and of a portion of the ratchet mechanism.

Fig. 11 is a perspective of the three elements which constitute the spring-pressed button for frictionally holding the transverse handle rod against endwise displacement.

Fig. 12 is an enlarged longitudinal sectional view of the element which constitutes the handle end of the tool, and which forms a part of the ratchet mechanism, and through which the transverse handle rod is inserted.

Fig. 13 is a perspective of the loose ratchet toothed ring which constitutes a part of the reversible ratchet mechanism.

Fig. 14 is an enlarged cross section on line 5 14—14 in Fig. 3.

As thus illustrated, the invention comprises an outer tube 1 which serves as the shank or body of the wrench or other tool, and which is provided with upper and lower 10 knurled portions 2 and 3 which are spaced apart to indicate the different positions necessary or desirable for one hand of the operator or user when the wrench is used under different circumstances, while the 15 other hand is engaged in rotating the handle of the wrench. Said handle comprises a rod 4 which is inserted through the openings 5 of the handle head 6, the latter having a bore 7, a larger bore 8 and a still larger bore 9 at the upper end thereof. The lower end of this cylindric handle head is provided with ratchet teeth 10, as will herein-after more fully appear, and the walls of the element thus formed and arranged are 20 provided with upper and lower holes 11 and 12 the former for a screw 13, and the latter for the removal of the pin 14, for purposes which will hereafter more fully appear. A cylindric button 15 fits the bore 30 9, and a disk 16 also fits said bore, and rests on the shoulder 17, a spring 18 being enclosed in the cavity 19 of said button, whereby the latter is yieldingly pressed against the under side of the rod 4 to prevent end-wise displacement of the latter—that is to say, to prevent the rod from dropping out, but at the same time permitting the rod to be removed when the wrench is not in use. The screw 13 engages the recess 20 in the 40 side of the button 15, more or less loosely, thereby to prevent said button from falling out when the handle rod is removed, but permitting sufficient play or movement of the button to enable it to press against the 45 under side of the handle rod. A short section of tubing 21 fits the bore 7 and has the pin 14 inserted through its upper end, a spring 22 being interposed between said pin and the shoulder 23 formed on the inside of 50 the handle head, whereby said tube 21 is normally held in raised position against the bottom of the disk 16, but is capable of downward movement against the tension of said spring. The tube 21 is fastened by a pin 55 24, or in any suitable manner, to the head 25 of the extension tube 26, this head having ratchet teeth 27 on the upper side thereof. A loose ratchet toothed ring 28 is interposed between the teeth 10 and 27, it 60 being observed that said ratchet teeth of the ring 28 face in opposite directions, and that the teeth 10 and 27 are correspondingly shaped, so that a reversible ratchet mechanism is provided. To reverse the direction 65 of operation of the ratchet, a sliding ring

29 is arranged to slide up and down on the portions 30, 28 and 31, the effect being that the elements 28 and 31 are locked against relative rotation when this ring 29 is in raised position, while the elements 28 and 30 70 are locked against relative rotation when the ring 29 is moved downward into the position shown, for example, in Fig. 3, the raised position being shown in Fig. 2; and, in this way, there are really two ratchets 75 provided which operate in opposite directions, and by means of said sliding ring 29 either one ratchet or the other is rendered inoperative, so that oscillation of the handle head 6 will result in intermittent rotation 80 of the tube 26 in either one direction or the other, depending upon which ratchet is in use. The tube 26 is provided with a series of notches 32 for engaging the set screw 33 which is inserted laterally through the 85 side of the tube head 34, which latter is formed at the upper end of the tube 35, and the tube 26 is also provided at its opposite side with a longitudinal groove 36 for engagement with the spline or key-block 37, 90 the latter being held in a longitudinal recess 38 formed in the tube head 34, so that the tube 26 is free to slide endwise but cannot rotate relatively to the other tubes. A cap 39 is formed to screw upon the screw 95 threaded upper portion of the tube head 34, to hold the key 37 in place, and forms a seat for the head 25 when the tube 26 is telescoped as far as it can go within the other tubes. A transverse cross pin 40 is 100 inserted through the lower end of the tube 26, so that the end of this pin is at the lower end of the groove 36, and will engage the lower end of the key 37 when the tube 26 is raised to its highest position. When the 105 tube 26 is rotated, the tube 35 is thereby rotated within the shank or body tube 1, with the result that the socket piece 41 is also rotated. This socket piece is formed to engage a bolt head or nut, having a polygonal cavity 42 for this purpose. A universal joint 43, of any suitable character, connects the socket piece 41 with the lower end 110 of the rotary tube 35, so that the back and forth rotation of the handle will cause an intermittent rotation of the socket piece. It will be seen that the shank or body tube 1 has a laterally deflected lower end portion 44 in which the socket piece 41 rotates, said socket piece having an annular enlarged 115 portion 45 which is knurled to permit rotation thereof by the thumb and finger of the user. Also, it will be seen, this annular portion 45 is provided with a groove 46 on its upper side to receive the lower edge of 120 the portion 44 of the outside tube, so that a tight joint is provided, and whereby the socket piece is rotatably mounted on and engaged with the extreme lower end of the 125 outside tube or shank which forms the body 130

of the tool. Openings 47 are provided at opposite sides in the elbow between the portion 44 and the body of the tube 1 to permit removal of the pin 48 of the universal 5 joint—that is to say, so that this pin can be pushed out to permit separation of the socket piece 41 from the rotary tube 35 when such is necessary or desirable.

The socket piece recess 42 is shaped to fit 10 a certain size of nut or bolt, of course, but a supplemental socket piece 48 can be inserted in the cavity 42, being made to fit therein, and being provided with a socket 49 to receive a nut or bolt head of smaller size, 15 and with a plurality of these supplemental of extension socket pieces 48, having recesses or cavities of different sizes, the wrench or tool can be used in connection with nuts or bolt heads of various shapes and sizes. A 20 spring 50 is preferably inserted in the socket piece 41 to engage the notches 51 on the supplemental or extension socket pieces, thereby to prevent the latter from dropping out, but making it possible to easily insert or 25 remove each supplemental socket piece.

The ring 29 is preferably provided with a spring 52 to hold it frictionally in raised position, but it will be understood that the said reversible ratchet mechanism can be of 30 any suitable, known or approved character.

When the cap 39 is removed, the tube 26 can be raised until the pin 40 strikes the key 37, and by lifting the latter upwardly, the tube 26 can be entirely removed from the 35 upper end of the tube head 34, thus entirely disconnecting the extension tube from the other two eccentrically arranged and telescoped tubes 1 and 35, when this is necessary or desirable. When the set screw 33 is un- 40 screwed a distance, the tube 26 can then be adjusted endwise until the length of the wrench or tool has been increased to the desired extent, the groove 36 permitting such endwise adjustment, and the screw 33 can 45 then be tightened to engage one of the notches 32, whereby the extension tube is then locked in its adjusted or extended position.

Of course, during the oscillation or back 50 and forth operation of the handle 4 and handle head 6, the latter will rise and fall on the tube 21, as the ratchet teeth slide over each other and then settle into place, in the manner characteristic of a ratchet of 55 this general character, but the spring 22, while permitting this movement, serves to yieldingly keep the ratchet teeth in operative engagement.

By grasping the portion 45 between the 60 thumb and the finger, the socket piece 41 can be rotated, when this is necessary or desirable in starting the nut or bolt, in any situation in which it might be difficult to do this by oscillation or rotation of the handle.

65 The entire tube 1 could be knurled on

the outside, of course, but this is more or less expensive, and besides this would not provide two separate and distinct handle portions. For this reason, therefore, it is preferable to provide the two separately 70 formed or spaced portions 2 and 3, as this affords sufficient opportunity for shifting the hand from the lower portion to the upper portion of the tube 1, thus in effect indicating the two positions of the hand, 75 and at the same time reduces the cost of manufacture, inasmuch as the considerable intermediate portion of the tube 1 is allowed to remain smooth or without the knurled formation provided immediately 80 above and below this portion. For different situations, and for different lengthwise adjustments of the wrench, it is desirable sometimes to grasp the lower portion of the tube 1 and at other times to grasp the upper 85 portion of this tube, and the two separate knurled portions 2 and 3 constitute a sufficient and satisfactory provision for this purpose.

The angle of the portion 44 relatively to 90 the tube 1 can be changed or varied, of course, but the angle shown is about right and is preferable for the ordinary or usual situations in which the use of a wrench of this kind is desirable, as it affords opportunity for the rotation of a nut or bolt head about an axis which is at an angle to the axis about which the rotating instrumentalities are operated, so that the hand of the operator does not have to be in direct alignment with the bolt or nut. The usual advantages, however, of a wrench of this general character are so well known and understood, that further explanation thereof is unnecessary. As shown, the portions 28, 95 30 and 31 are preferably hexagonal, and the interior of the ring 29 is also hexagonal, so that said ring will lock the ring 28 to the portion 30 or the portion 31, in the manner described, thereby to render either one 100 ratchet or the other inoperative. Of course, though, as explained, the ratchet mechanism may be of any suitable character and may be given any suitable or desired formation.

What I claim as my invention is:—

1. In a wrench or tool of the class described, the combination of an outer stationary tube forming a shank or handle, an inner rotary tube, an extension tube telescoped within the rotary tube, said extension tube having a longitudinal groove therein, and means engaging said groove to prevent relative rotation between said rotary tube and said extension tube, together with a tool-like device connected with the rotary tube 120 and a handle connected to the extension tube.

2. A structure as specified in claim 1, said means comprising a removable key, the rotary tube having means to hold the key in place.

3. A structure as specified in claim 1, said extension tube having a series of notches at one side thereof, and the rotary tube having means for engaging said notches, whereby 5 the rotary tube and the extension tube may be locked in adjusted position.
4. In a wrench or tool of the class described, the combination of a shank or body forming one handle of the tool, a tool-like 10 device at the lower end of said shank, an inner rotary tube connected to said device, an extension tube in said rotary tube, means including a longitudinal groove in the extension tube and means at the outer end of 15 the rotary tube for engaging this groove to form a spline and to movably connect the rotary tube with the extension tube, so that rotation of the extension tube will rotate the rotary tube, means permitting total dis- 20 connection of the extension tube from the upper end of the rotary tube without disconnecting the rotary tube from said device, and a second handle connected to the exten- sion tube.
5. A structure as specified in claim 4, said means for permitting disconnection of the extension tube from the rotary tube comprising a cap screwed upon the upper end of the rotary tube.
6. In a wrench or tool of the class de- 30 scribed, the combination of an oscillatory or rotatable handle head, a transverse handle rod slidably inserted through said head, a button fitted in the head to engage said rod, 35 a disk in said head, and a spring interposed between the disk and the button, together with means to prevent the button from being displaced from the head when said rod is withdrawn from the head.
7. In a wrench or tool of the class de- 40 scribed, the combination of an outside tube forming a shank or first handle for the tool, a socket piece rotatably mounted in one end of said tube, at an angle thereto, means espe- 45 cially provided on said socket piece to form a second handle to permit easy and convenient rotation thereof by the thumb and finger, and a third handle and means includ- 50 ing a longitudinally grooved extension tube engaged by means forming a spline at the outer end of said shank and whereby this handle is connected to said socket piece, with a disconnecting screw cap forming a fourth handle adjacent the spline between the first handle and the third handle.
8. A structure as specified in claim 7, said means comprising a knurled ring-like portion on the socket piece, which portion is formed with a groove to receive therein the 55 end of said tube.
9. In a wrench or tool of the class de- 60 scribed, the combination of an outside tube forming a shank or first handle, a rotatable tool-like device forming a second handle at the lower end of said shank, a third handle and means including a longitudinally grooved extension tube engaged by means 65 forming a spline at the outer end of said shank and whereby this handle is connected to rotate said device, means forming a grip near the upper end of said tube, the two 70 grips being spaced apart and having a smooth surface of the tube between them, so that two definite and predetermined posi- 75 tions for the hand are indicated on said tube, and disconnecting means at the top of the first handle adjacent the spline to permit disconnection between the third handle and said device.
10. A structure as specified in claim 9, the connection between said device and the handle by which it is rotated comprising an ex- 80 tension tube, in combination with means for holding said extension tube in adjusted position.

JOSEPH RENÉ AYOTTE.
